UNITED STATES PATENT OFFICE.

STANLEY W. MILLS AND LIONEL SCHMIDT, OF POUGHKEEPSIE, NEW YORK, ASSIGNEES
TO F. I. A. T., A CORPORATION OF NEW YORK.

WIND-SHIELD.

1,199,808.

Specification of Letters Patent.

Patented Oct. 3, 1916.

Application filed October 6, 1913. Serial No. 793,599.

To all whom it may concern:

Be it known that we, STANLEY W. MILLS, a citizen of the United Kingdom of Great Britain, and LIONEL SCHMIDT, a citizen of the United States of America, residing at 5 Poughkeepsie, in the county of Dutchess and State of New York, have invented certain new and useful Improvements in Wind-Shields, of which the following is a full, 10 clear, and exact specification.

This invention relates to wind shields, more particularly intended for automobiles, and has especial reference to improvements in the general organization and adjustability thereof whereby the number of parts is reduced and a greater range of adjustability attained.

A further object of the invention is to provide a wind shield which will be of ornamental appearance on the automobile, and which will be strong, simple to operate and not subject to rattling or to objectionable whistling of the wind through interstices.

The wind shield of this invention comprises in its broadest aspect upright standards carrying a sash pivoted thereto at the top portion, so that the lower portion will be adjustable to any desired angle of inclination relatively to the standards. When it is 20 not desired to use the wind shield, the adjustable sash is swung to a horizontal position somewhat above the line of vision of the driver, so that free view and access of air are permitted, while by adjusting the 30 position more or less to the vertical, clear vision is provided under unfavorable atmospheric conditions.

In the specific form of the invention herein illustrated, the standards are horizontally 40 pivoted at their lower ends, so that they can be inclined independently of the movable sash, and these standards carry a lower sash which is preferably made stationary relatively to the standards. In this form, the 45 standards are interconnected by a shaft including the axis of pivoting, and between the supporting pivot or brackets is provided a filler piece which not only closes the space between the lower side of the sash and the 50 shaft at any desired inclination of the standards, but conceals the shaft and substantially enhances the ornamental appearance of the entire structure. In this form, it is possible to not only incline both sash together, but to incline the upper sash to any

desired extent independently of the lower sash.

The invention will be more fully understood in connection with the description of the accompanying drawings wherein—

Figure 1 is an elevation showing the rear side of the shield; and Fig. 2 is a side elevation.

1 represents the cowl or other part to which the shield is attached.

2, 2 represent brackets rigidly secured to the cowl by bolts 3. The brackets 2 are provided with horizontally alined sockets in which are journaled standards 4. As herein shown, the standards 4 are rigidly secured 60 to blocks 5 to which are pinned steel bushings 6, and the blocks 5 are connected by a shaft 7 pinned thereto at its ends, as by pins 8. The standards 4, the blocks 5 and the shaft 7 thus constitute a U-shaped frame, 70 the upper ends of which swing toward and from the vertical on the axis of shaft 7. Preferably rigidly secured to the standards 4, as by screws 9 and lugs 10 is a lower sash 11 provided with a glass or other transparent material 12. 13^a is a binding strip which may or may not be used as desired. The lower end of the sash 11 is thus spaced above the shaft 7, and in order to conceal the shaft 7 and at the same time close the space between the brackets 2, a filler piece 13 is provided. This is preferably of wood U-shaped in cross section, and provided with a cylindrical curved surface 14 on its upper side matching the curvature of the upper side of 80 brackets 2 and closely fitting the lower edge of sash 11 so that the air will not pass therethrough sufficiently to produce an objectionable draft or whistling.

15 represents thumb screws threaded on 95 bolts 16, which lock the bushings, and hence the entire frame against rotation when tightened up.

17 represents an upper sash carrying the glass 18 and provided with trunnions 19 100 journaled in bearings 20 and carried by the upper ends of standards 4. These trunnions 19 are clamped by bolts 21 and thumb screws 22 constructed similarly to the thumb screw 15 and bolt 16. A detail of these clamps is 105 shown in Fig. 2, in which it will be seen that the bolt 21 is provided with a head 23 having one side cut away as at 24, to engage the circular surface of trunnion 19, and thumb screw 22 engages a movable simi- 110

larly-shaped block 25, so that the forcing of these two blocks together firmly clamps the trunnion or the bushing 6, as the case may be.

- 5 In Fig. 1, it will be observed that the trunnions 19 are carried by corner pieces 26, which are firmly secured to the sash 17, and each trunnion is provided with a cap 27 and secured thereto by screw 28 so that 10 the standards 4 are tied together at their upper ends through bearings 20, cap 27, screw 28, corner piece 26 and sash 17. This construction is of particular importance in a wind shield for an automobile inasmuch 15 as vibration and rattling are not only objectionable but eventually lead to the breaking of the glass, and by this construction these objections are avoided. It will also be seen that the lower sash will not be cramped 20 with consequent liability of breaking, either when the entire shield is inclined or when the upper sash is adjusted, while the adjustment of the entire shield is controlled by four easily accessible clamps.
- 25 It will be seen that the frame may be rigid if desired, and the two sash shown may be combined into one sash pivoted at its top if desired, without departing from the scope of the invention, and various 30 other changes and modifications may be made, all within the scope of the appended claims.

Having thus described our invention, we declare that what we claim as new and desire to secure by Letters Patent is:—

1. A wind shield comprising in combination with a support oppositely disposed brackets, standards horizontally pivoted to said brackets, a shaft connecting said standards between said brackets, a stationary filler piece attached to said support between said brackets and covering said shaft, and a sash horizontally pivoted to said standards. 40
2. A wind shield comprising in combination with a support oppositely disposed brackets, standards pivotally mounted at their lower ends on said brackets, a sash carried by said standards, a shaft connecting said standards below said lower sash, a 45 stationary filler piece attached to said support between said brackets, said filler piece being in part between said shaft and said lower sash and being exteriorly curved to permit movement of said standards and 50 lower sash and maintain substantial continuity of surface.
3. A wind shield comprising in combination with a support oppositely disposed

brackets, standards horizontally pivoted to said brackets, a sash carried by said standards above the axis of pivoting, and a filler piece between said brackets and said support having its upper surface curved to fit the lower edge of said sash at any desired position.

65

4. A wind shield comprising in combination with a support oppositely disposed brackets, a U-shaped frame horizontally pivoted at the bottom in said brackets, a lower sash carried by said frame above the 70 bottom, a stationary filler piece between said brackets and said support having its upper surface curved to fit the lower edge of said sash at any desired position and inclosing the bottom of said frame, and an upper sash 75 pivoted at its upper portion to said frame and having its lower edge adjustable relatively to said frame and lower sash.

80

5. A wind shield comprising oppositely disposed brackets, a U-shaped frame horizontally pivoted at the bottom in said brackets, a filler piece between said brackets inclosing the bottom of said U-shaped frame, a sash hinged at the upper ends of said frame, and means connecting the said 85 ends to the sash frame to stiffen said ends.

6. A wind shield comprising oppositely disposed brackets, a U-shaped frame horizontally pivoted at the bottom in said brackets, a filler piece between said brackets 90 inclosing the bottom of said U-shaped frame, a sash hinged at the upper ends of said frame, means connecting the said ends to the sash frame to stiffen said ends, and clamping means for said sash independent 95 of said top connection between said frame ends.

7. A wind shield comprising in combination with a support oppositely disposed brackets, a U-shaped frame horizontally pivoted at the bottom in said brackets, a stationary filler piece between said brackets and said support inclosing the bottom of said U-shaped frame, a sash hinged at the 100 upper ends of said frame, and clamps extending transversely to said pivots of the frame and the sash for adjustably locking them in position.

In testimony whereof, we affix our signatures in the presence of two witnesses.

STANLEY W. MILLS.
LIONEL SCHMIDT.
